UNITED STATES PATENT OFFICE.

EDMUND C. PEARSON, OF NEWBURYPORT, MASSACHUSETTS.

DESIGN FOR A CRACKER, &c.

SPECIFICATION forming part of Design No. 20,662, dated April 7, 1891.

Application filed February 24, 1891. Serial No. 382,676. Term of patent 7 years.

To all whom it may concern:

Be it known that I, EDMUND C. PEARSON, a citizen of the United States, residing at Newburyport, in the county of Essex and State of Massachusetts, have invented and produced a new and original Design for Biscuits, Crackers, Cakes, and Kindred Articles, of which the following is a specification, reference being had to the accompanying drawings, forming part thereof.

This invention relates to a novel design for biscuits, crackers, cakes, and kindred articles, the leading feature of the design consisting in the outline form or contour of the article, as hereinafter set forth.

In the said drawings, A represents a biscuit, cracker, or cake, which is made in the form or shape of a parallelogram, the edges being indented to produce a scalloped outline, as

shown, and in each of the four sides or edges, 20 at the center, is formed a notch b, of semicircular form, the design thus produced being unique and attractive to the eye.

What I claim as my invention, and desire to secure by Letters Patent, is—

The design for biscuits, crackers, cakes, &c., the same consisting of a parallelogram A, having its edges indented to produce a scalloped outline and provided with a semicircular notch b at the center of each of its 30 four sides or edges, substantially as herein shown and described.

Witness my hand this 19th day of February, A. D. 1891.

EDMUND C. PEARSON.

In presence of—

P. E. TESCHEMACHER,
HARRY W. AIKEN.
